UNITED STATES PATENT OFFICE.

FRED B. HARTL, OF CHICAGO, ILLINOIS.

TIMER WIRE SYSTEM.

1,371,419.

Specification of Letters Patent. Patented Mar. 15, 1921.

Application filed May 26, 1919. Serial No. 299,930.

To all whom it may concern:

Be it known that I, FRED B. HARTL, a citizen of the United States, residing at Chicago, in the county of Cook and State of 5 Illinois, have invented certain new and useful Improvements in Timer Wire Systems, of which the following is a specification.

This invention relates to improvements in timer wire systems and more particularly to 10 connectors for such systems and its object is to provide a single connector or coupling adapted to be fastened direct to the timer arm to connect the flexible wire conduit to the timer casing and to carry the ends of the 15 electrical conductors that extend to the timer binding posts. The invention consists in the combination and arrangement of parts to be hereinafter fully described, pointed out in the appended claims and illustrated in the 20 accompanying drawing which forms a part of this specification and in which—

Figure 1 is a plan view of a timer system constructed according to my present invention.

25 Fig. 2 is a side view of Fig. 1.

Fig. 3 is a side view of the connector.

Figs. 4 and 5 are side views of the companion sections of the connector.

Like reference characters denote corresponding parts throughout the several views.

The reference numeral 1 denotes the timer casing, 2 the binding posts and 3 the timer arm. My connector proper comprises the angular bracket composed of twin angular 35 bracket sections each of said sections being of channel-like formation and comprising a central integral portion 5 and terminal portions 6, 7, the said terminal portions being disposed at an angle to the central portion, 40 the terminal portion 6 being formed with a beveled portion 8 and the terminal portion 7 being formed with the beveled portion 9, the central portion 5 of each bracket section being formed with the semi-circular peripheral grooves 10 and the bracket sections 45 being formed with the perforations 11, 12, the latter perforation in each bracket section being to receive the timer arm and the timer rod (not shown).

50 The bracket sections are assembled with

their concave sides adjacent so that a tubular bracket is formed, one end of said bracket embracing the timer arm and the other receiving the wire conduit 13, said bracket sections being retained in operative position 55 by the screw 14 which extends through the perforations 11 which perforations are aligned in the assembled position of the bracket sections as are also the semi-circular grooves 10 through which the insulated 60 electrical conductors 15, 16 extend that connect with the binding posts 2. All of the electrical conductors 15, 16 as well as the wire conduit 13 are thus united in the one connector the sections of which are firmly 65 connected to each other and to the timer arm 3 directly by the screw 14.

What is claimed is:—

1. In timer wire systems, a sectional perforated bracket adapted for terminal engagement with the timer arm, and a binding element whereby said bracket sections are firmly retained in assembled position and in fixed engagement with said timer arm.

2. In timer wire systems, a sectional perforated bracket, the perforations thereof being adapted to receive the timer arm, timer rod and insulated electrical conductors, and a binding element whereby said bracket sections are firmly retained in assembled position and in engagement with said timer arm.

3. In timer wire systems, a sectional perforated bracket, each bracket section comprising a central portion and terminal portions disposed at an angle to said central portion, said central portion having its component sections grooved to receive the electrical conductors, one terminal portion being perforated to receive the timer arm, and a screw for binding said bracket sections to 90 each other and to the timer arm.

In testimony that I claim the foregoing as my own I have hereto affixed my signature in the presence of two subscribing witnesses.

FRED B. HARTL.
